[57] CLAIM

The ornamental design for table, as shown and described.

DESCRIPTION

FIG. 1 is a perspective view of the table of the present invention;

FIG. 2 is a side view of the table of FIG. 1;

FIG. 3 is a front view of the table of FIG. 1;

FIG. 4 is a top view of the table of FIG. 1;

FIG. 5 is a bottom view of the table of FIG. 1; and,

FIG. 6 is a cross section view of a leg.

The front and back views are substantially identical as are the side views.
